UNITED STATES PATENT OFFICE.

FRANK C. McCUSKER, OF PHILADELPHIA, PENNSYLVANIA.

ROOFING-TONGS.

No. 865,930.

Specification of Letters Patent.

Patented Sept. 10, 1907.

Application filed June 29, 1907. Serial No. 381,475.

To all whom it may concern:

Be it known that I, FRANK C. McCUSKER, a citizen of the United States, and a resident of Philadelphia, in the county of Philadelphia and State of Pennsylvania, 5 have invented certain new and useful Improvements in Roofing-Tongs, of which the following is a specification.

My invention is an improvement in tinnings' tongs designed for use in bending or forming the seaming lips 10 used in making the seams of tin roofs; and the invention consists in certain novel constructions and combinations of parts as will be hereinafter described and claimed.

In the drawings Figure 1 is a perspective view of 15 tongs embodying my invention. Fig. 2 is a detail view of the jaw carrying the gage plate, the latter being in place. Fig. 3 is a detail view of the inner side of the other jaw, and Fig. 4 is a detail perspective view, portions being broken away, of the gage plate.

20 The tongs, as shown, comprise the jaws A and B which for convenience of reference I term the under and upper jaw, the jaw A carrying the gage plate and the jaw B being constructed to coöperate with the jaw A and the gage plate in the use of the invention. These 25 jaws A and B are provided, respectively, with handle bars C and D which are pivoted together at E, and a spring F on the handle bar D above the pivot E engages with the pin G on the handle bar C and operates to open the jaws after the seam flange is bent and the 30 handle bars are released so the jaws may be slipped along to position to operate upon the joined portions of the tin. This spring F and its coöperating part G are useful in that they avoid the necessity of workmen opening the jaws as the spring opens the jaws instantly 35 on releasing the handle bars, in the operation of the invention.

The jaw A is shown as a flat plate which may be slotted and perforated in order to lighten it and it is made of sufficient width to properly support the gage 40 plate H, which latter rests flat against the inner face of the lower jaw A, has its ends h bent alongside the ends of the jaw A to aid in guiding the gage plate, and has a lower straight edge I, is provided near the ends of its lower straight edge I with forwardly projecting stop 45 lugs J and has the upwardly projecting arms K near its opposite ends, which arms are slotted at L, and rest flat upon the lower jaw A so they may slide with the gage plate up and down on the said jaw when the clamping devices are released. The clamping devices 50 are shown as threaded studs M projecting outwardly from the upper face of the lower jaw A through

the slots L of the arms K and receiving winged nuts N which may be tightened to secure the arms K and the gage plate in any desired adjustment.

The jaw A is provided near its ends with a graduated scale O with which the gage plate registers, so it may be accurately set to form seaming strips of any desired height.

The upper jaw B is made narrower than the lower jaw A so it will not interfere with the operation of the 60 winged nuts N and it is provided with the slots P leading from its upper edge and receiving the stop lugs J, the jaw B being provided with the bridge connections Q over the upper ends of the slots P and reinforcing the jaw B at its upper edge giving it the necessary 65 strength at its slotted portions.

An important feature of my invention is the adjustable gage plate in the particular construction shown, which can be set on the lower jaw of tongs in such manner as to form a seaming lip of any desired width. As 70 is well understood it is necessary for tinnings to employ several tongs each designed for forming the lip of a corresponding width. By my improved tongs the gage plate can be conveniently set to form a lip of any suitable width and the gage plate can be adjusted 75 quickly to the desired position whenever occasion requires.

The gage plate is carried on the lower jaw and clamping devices for said gage plate are also carried on the said jaw in convenient reach of the operator, and the 80 devices for securing the adjustment of the tongs do not materially add to the weight of the tongs, as will be understood from the drawings and foregoing description.

I claim—

1. The tongs herein described comprising the lower or 85 main jaw provided at its ends with the graduated scales and having near said ends the upwardly projecting threaded studs, the gage plate provided at its lower edge near its ends with the upwardly projecting stop lugs and having the slotted arms extending along the face of the tongs 90 jaw with the slots thereof receiving the threaded studs, the winged nuts on said studs, the upper jaw provided with the transverse slots receiving the stop lugs of the gage plate and also having the bridge connections extending over the said slots and reinforcing the tongs jaw, the 95 gage plate having its main or body portion arranged and operating between the inner faces of the opposing tong jaws and extending approximately throughout the length of said jaws handle bars secured to their respective jaws and pivoted together and the spring acting upon the said 100 handle bars to open the jaws when the handle bars are released, substantially as set forth.

2. An adjustable roofing tongs comprising a jaw plate provided near said ends with the forwardly projecting threaded studs, the gage plate fitting against the said 105 jaw and having at its lower edge upwardly projecting stop

lugs and also provided with the projecting arms slotted longitudinally with the slots thereof fitting over the threaded studs, nuts on the studs for securing the gage plate in any desired adjustment and the jaw having slots 5 receiving the stop lugs of the gage plate, the gage plate having its main or body portion arranged and operating between the inner faces of the opposing tong jaws and extending approximately throughout the length of said jaws, substantially as set forth.

3. A roofing tongs having jaws and pivoted handle bars 10 and provided with a spring on one of the handle bars and a pin on the other handle bar for engagement by said spring, the latter operating to open the jaws when the handle bars are released, substantially as set forth.

FRANK C. McCUSKER.
